UNITED STATES PATENT OFFICE.

MAX R. LEHMAN, OF QUINCY, ILLINOIS, ASSIGNOR TO EXCELSIOR STOVE & MANUFACTURING COMPANY, OF QUINCY, ILLINOIS, A CORPORATION.

DESIGN FOR A HEATING-STOVE.

SPECIFICATION forming part of Design No. 37,471, dated June 20, 1905.

Application filed May 16, 1905. Serial No. 260,683. Term of patent 7 years.

To all whom it may concern:

Be it known that I, MAX R. LEHMAN, a citizen of the United States, residing in Quincy, in the county of Adams and State of Illinois, have invented a new, original, and ornamental Design for Heating-Stoves.

The accompanying drawings illustrate my new, original, and ornamental design for heating-stoves.

In the drawings, Figure I is a perspective

view of the front of the heating-stove. Fig. II is a perspective view of the reverse side of the heating-stove.

I claim—

The ornamental design for a heating-stove, 15 as shown.

MAX R. LEHMAN.

In presence of—

A. J. ROBINSON,
J. B. ULLMEN.
